UNITED STATES PATENT OFFICE.

CHARLES JOHN SAGEBRECHT, OF BROOKLYN, NEW YORK, ASSIGNOR TO INTERSTATE ELECTRIC NOVELTY COMPANY, A CORPORATION OF NEW YORK

CASING FOR PORTABLE ELECTRIC FLASH-LIGHTS.

1,187,103.

Specification of Letters Patent. Patented June 13, 1916.

Application filed December 18, 1915. Serial No. 67,516.

To all whom it may concern:

Be it known that I, CHARLES J. SAGEBRECHT, a citizen of the United States of America, residing at Brooklyn, county of Kings, and State of New York, have invented certain new and useful Improvements in Casings for Portable Electric Flash-Lights, of which the following is a full, clear, and exact description.

10 This invention relates to improvements in casings for portable electric flashlights, the object being to provide a casing having embedded in the wall thereof a conductor or conductors for the completion of the circuit for the lamp and battery supported by the casing, a suitable circuit-closer being provided to close the circuit between said embedded conductors, the said circuit-closer being preferably carried by the casing.

15 20 To carry out my invention I provide a casing which is preferably molded around a conducting element so as to entirely cover the conductor, by which means the said conductor is protected from injury and also 25 against climatic changes.

To produce an efficient and at the same time an inexpensive mechanism, I employ conducting elements consisting of a plurality of tubes of thin metal, one end of each tube being threaded to receive a cap, the casing being molded around said tubes, the threaded portion of each tube, however being uncovered, or partly so. The tubes referred to will be slightly separated at adjacent ends and a circuit-closer will be employed to close the circuit between said tubes. Further features of improvement will hereinafter appear.

I will now proceed to describe my invention in detail, the novel feature of which I will point out in the appended claims, reference being had to the accompanying drawing, forming part hereof, wherein—

Figure 1 illustrates a vertical sectional view of a flashlight casing constructed in accordance with my improvement, a battery and lamp being shown in elevation. Fig. 2, is a bottom plan view of the casing, the other parts being omitted. Figs. 3 and 4 are perspective views of the upper and lower tubular conductors, respectively.

In the drawing, 1 indicates a casing of non-conducting material arranged to receive and hold a battery 2 which supplies current for a lamp 3 carried by a reflector 4 covered

by a lens 5. As is usual, the lamp 3 rests in contact with the carbon-pole 6 of the battery 2, the circuit being closed for the lamp through the conductors which are embedded in the casing by means of the circuit-closer hereinafter described. The conductors which are embedded in the casing consist of tubular members indicated by 8 and 9. The conductors 8 and 9 are spaced apart at the adjacent ends 10 and 11, respectively, as shown in Fig. 1.

To provide for the securement of the caps 12 and 13, the outer end of each tubular conductor 8 and 9 is threaded as at 14 and 15, respectively. The lower cap 13 electrically connects the zinc-pole of the battery and lower tubular conductor 9 by means of the spring 14^a. The upper conductor 8 is electrically connected to the lamp 3 by means of the reflector 4 into which the lamp is screwed. The reflector 4 rests in contact with the flange 14^a carried by the conductor member 8. The lens 5 is held in place by the cap 12 which engages the threads on the conductor 8.

To connect the conductors 8 and 9 with the circuit closing elements, consisting of the slidable contact 7^a and fixed contact 16, I provide the conductor 8 with a tongue 17 and the conductor 9 with a tongue 18. The tongues 17 and 18 pass out through the casing 1 and are secured to their respective circuit-closer elements 16 and 7^a. The slidable contact 7^a is held by a bracket 19^a upon which it can be moved back and forth. Any suitable circuit closing means can be used.

To form the casing, the tubular conductors will be suitably positioned in a mold and the material for the casing 1 poured around them, the threaded end of the conductor 9 projecting beyond the casing 1. The mold will be designed to prevent the threads 14 at the outer end of the conductor 8 from being covered.

It will be apparent that the conductors will at all times be protected and will also be concealed; furthermore, by employing these tubular conductors an exceedingly strong casing will be formed, as the said conductors will act as reinforcements for the casing wall, besides performing the function of elements of an electrical circuit.

After the casing has been formed, with the conductors 8 and 9 embedded therein,

the tongues 17 and 18, which will project beyond the casing wall, will be bent over to lie against the outer surface of the casing wall, after which the circuit-closer elements 7 and 16 will be attached thereto in any desirable manner. After the reflector 4 with its lamp 3 has been placed in position, the cap 12 applied, battery 2 inserted, and cap 13 with its spring 14 attached, the apparatus is ready for use by merely sliding the contact 7^a forward to touch the contact 16, which will close the circuit for the lamp.

Having now described my invention, what I claim and desire to secure by Letters Patent is:—

1. In combination with a battery and a lamp and lens mounted thereon, an inclosing casing, hollow metallic bracing and conducting means of similar form embedded in said casing, but protruding at the ends of the latter and screw-threaded in their protruding ends, caps screwed on said ends,

electrical connections held by said caps between them and the poles of said battery, one of said caps being adapted to hold said lens in place.

2. In combination with a battery and a lamp mounted thereon, a cylindrical inclosing casing, a pair of metallic cylinders embedded in said casing, with an interval between them but protruding at the ends of said casing and screw-threaded in their protruding ends, caps screwed on said ends, electrical connections held by said caps between them and the poles of said battery, and circuit closing devices arranged to extend at will across the interval between said metallic cylinders and complete the circuit.

Signed at city of Toronto this 15th day of December, 1915.

CHARLES JOHN SAGEBRECHT.
